UNITED STATES PATENT OFFICE.

JILES W. STRAIT, OF JEFFERSONVILLE, OHIO.

SHOCK-BINDER.

1,250,046.

Specification of Letters Patent. Patented Dec. 11, 1917.

Application filed March 14, 1917. Serial No. 154,732.

To all whom it may concern:

Be it known that I, JILES W. STRAIT, a citizen of the United States, residing at Jeffersonville, in the county of Fayette and 5 State of Ohio, have invented certain new and useful Improvements in Shock-Binders; and I do hereby declare the following to be a full, clear, and exact description of the invention, such as will enable others skilled 10 in the art to which it appertains to make and use the same.

This invention relates to a binder for fodder shock, and the primary object of the invention is to provide a device for securely 15 binding or drawing together a shock of corn stalks for holding the same while it is tied by the usual type of binder twine or other tie.

Another object of this invention is to 20 provide a device as specified, which comprises a main body plate having an eye formed on one end of the same and a hook formed upon the other end of the same, through the center of which body plate ex- 25 tends a substantially rectangular pin upon which a rope clamping spring is mounted, and further to provide a rotary cam which has a handle formed thereon and a pair of inclined depending extensions which engage 30 the rope clamping spring and force it outwardly away from the body of the rope clamp for allowing the rope to be drawn freely through the eye and hook for drawing the rope about a shock of fodder.

35 With the foregoing and other objects in view, this invention consists in such novel features of construction, combination and arrangement of parts as will be hereinafter more fully described, illustrated in the accompanying drawings and claimed.

40 In describing the invention in detail, reference will be had to the accompanying drawings wherein like characters designate like and corresponding parts throughout the 45 several views, and in which:—

Figure 1 is a top plan of the fodder binder;

Fig. 2 is a bottom plan of the rope clamp employed in the binder;

50 Fig. 3 is a side elevation of the clamp, showing the rope clamping spring in a rope engaging position;

Fig. 4 is a view similar to Fig. 3, showing the rope clamping spring forced outwardly 55 in an inoperative position; and

Fig. 5 is a section on the line 5—5 of Fig. 1.

Referring more particularly to the drawings, 1 designates the main body plate of the rope clamp and guide of the shock 60 binder which body plate has an eye 2 formed upon one end and a hook 3 formed upon the other end. The rope 4 is passed through the eye 2 and through the loop of the hook 3 and about a shock of corn stalks or other 65 fodder, and it is drawn tightly about the shock for forcing the stalks together and for holding them while being tied with the usual type of cord tie, by means of a rope clamping spring 5 which is attached to the 70 body 1 by means of a bolt 6. The majority of the shank of the bolt 6 is rectangular in shape as clearly shown in Fig. 5 of the drawings so as to prevent turning movement of the rope clamping spring with respect to 75 the body 1.

A cam structure 7 is provided which is rotatably mounted upon a collar 8. The collar 8 is mounted upon the rectangular portion of the shank of the bolt 6 intermediate the body 1 and the spring 5. The cam structure 7 includes a main body plate 9 which has a handle 10 formed thereon and extending outwardly therefrom. The handle 10 is bent upwardly as shown at 11 for 80 engagement with the edge of the body 1 for limiting the rotary movement of the cam 7. A pair of diametrically opposed depending bosses 12 are formed upon the under surface of the cam body 9 and they have 85 their under surfaces inclined as shown at 13 for engaging and riding over the upper surface of the spring 5 for forcing the rope engaging ends of the spring outwardly 90 away from the body 1 as shown in Fig. 4 of 95 the drawings, and out of a rope engaging position for allowing the rope 4 to pass freely through the eye 2 and the loop of the hook 3.

The end of the spring 5 terminates inwardly of the outermost portion of the eye 100 2 and the loop of the hook 3, so as to allow the rope 4 to run freely through the eye if desired, without engaging the spring.

In the use of the improved shock binder; the cam 7 is rocked or rotated through the 105 medium of the handle 10 for forcing the free ends of the spring 5 outwardly out of a rope engaging position, and the rope 4 is moved out of the loop of the hook 3 and passed about a shock of fodder. After the 110

rope is passed about the shock of fodder, the end which extends through the eye 2 may be passed beneath the end of the spring 5 after which the cam 7 is rotated for allowing the spring to securely clamp this end of the rope. The end of the rope which passes through the loop of the hook 3 is then pulled upon until the desired tightness of the shock is provided after which the end of the rope 10 is passed into the hook and beneath the spring 5. The spring 5 engaging the ends of the rope, will clamp the rope against the body 1 and prevent its slipping, thereby holding the shock tightly bound until the 15 permanent tie or binder is put about the shock after which the cam 7 is rocked for forcing the spring outwardly for releasing the rope 4 to allow the rope to be removed from about the shock of fodder.

20 In reducing the invention to practice, certain minor features of construction, combination and arrangement of parts may necessitate alterations to which the patentee is entitled, provided such alterations are 25 comprehended within the scope of what is claimed.

What is claimed is:—

1. In a fodder binder, a body plate, a flat spring connected to said body plate, a rope, 30 said spring adapted to engage said rope for clamping the rope in engagement with the body plate for preventing accidental movement of the rope independently of the body plate, and means carried by said body plate for forcing the rope engaging ends of the 35 spring outwardly away from the body plate to allow free unimpeded movement of the rope.
2. In a fodder binder, a body plate having 40 an eye formed upon one end thereof, a hook formed upon the opposite end of the body plate, a flat spring carried by said body

plate, a rope passing through said eye and through said hook, the ends of said spring adapted to engage said rope for clamping 45 it against said body plate for preventing accidental movement of the rope, a cam member rotatably carried by said body plate and positioned between the body plate and the spring, depending bosses formed upon 50 the under surface of said cam and having their under surfaces inclined and adapted for engaging said spring for forcing its ends outwardly away from said body plate to allow free unimpeded movement of said 55 rope.

3. In a fodder binder, a body plate having an eye formed upon one end thereof, a hook formed upon the opposite end of the body plate, a flat spring carried by said body 60 plate, a rope passing through said eye and through said hook, the ends of said spring adapted to engage said rope for clamping it against said body plate for preventing accidental movement of the rope, a cam member 65 rotatably carried by said body plate and positioned between the body plate and the spring, depending bosses formed upon the under surface of said cam and having their under surfaces inclined and adapted for engaging said spring for forcing its ends outwardly away from said body plate to allow 70 free unimpeded movement of said rope, a handle formed upon said cam member, said handle being bent intermediate its ends so that it will engage said body for limiting the rotary movement of the cam.

In testimony whereof I affix my signature in presence of two witnesses.

JILES W. STRAIT.
